DESIGN FOR A BILL CLIP

Edmond Foret, New York, N. Y., assignor to Cartier, Inc., New York, N. Y., a corporation of New York

Application May 29, 1941, Serial No. 101,222

Term of patent 7 years

To all whom it may concern:

Be it known that I, Edmond Foret, a citizen of France, residing at New York city, in the county and State of New York, have invented a new, original, and ornamental Design for a Bill Clip, of which the following is a specification, reference being had to the accompanying drawing, forming part thereof.

Figure 1 is a face view of a bill clip showing my new design.

from the top of Figure 1.

from the bottom of Figure 1.

I claim:

The ornamental design for a bill clip, as shown.
EDMOND FORET.
